(57) CLAIM

The ornamental design for a low profile captive screw, as shown and described.

DESCRIPTION

FIG. 1 is a top plan view of a captive screw of the present invention with a Philips driver recess.

FIG. 2 is a bottom view of the captive screw of FIG. 1.

FIG. 3 is a side elevation view of the captive screw of FIG. 1, the captive screw having a knob, a ferrule, a sleeve and a screw, showing the captive screw with the screw threads in a fully extended configuration, the remaining side being identical.

FIG. 4 is a perspective view of the captive screw of FIG. 1, showing the captive screw with the screw threads in a fully extended position.

FIG. 5 is a side elevational view of the captive screw of FIG. 1, showing the captive screw with the screw threads in a fully contracted configuration, the remaining sides being identical; and,

FIG. 6 is a perspective view of the captive screw of FIG. 1, showing the captive screw with the screw threads in a fully contracted position.

The phantom lines of FIGS. 1-6 are for illustrative purposes only and do not form part of the design of the captive screw.
